UNITED STATES PATENT OFFICE.

CHARLES E. BULLARD, OF WORCESTER, MASSACHUSETTS.

DESIGN FOR A BORDER FOR CARDS, &c.

SPECIFICATION forming part of Design No. 16,824, dated August 3, 1886.

Application filed May 24, 1886. Serial No. 203,161. Term of patent 3½ years.

To all whom it may concern:

Be it known that I, CHARLES E. BULLARD, a citizen of the United States, residing at Worcester, in the county of Worcester and State of Massachusetts, have invented and produced a new and original Design for the Border of Christmas Cards and Art Souvenirs, of which the following is a specification, reference being had to the accompanying drawings, forming part thereof.

Figure 1 represents a face view of a card or art souvenir with my newly-designed border. Fig. 2 represents face views of different styles or modifications of the card or souvenir shown in Fig. 1 with my newly-designed border.

My design is for the border of Christmas cards and art souvenirs or other similar articles; and it consists, essentially, in the ornamentation of the border of the card or similar article to produce an entirely novel and pleasing effect to the eye.

In the drawings, the part marked A is the central part of a Christmas card or souvenir, which may be ornamented with any pictorial representation or design, as the same forms no

part of my present design. The part marked B is the border, which extends around or incloses the central part, A, of the card. The border B may extend only upon two sides of the central part, A, as shown in some of the 30 modifications in Fig. 2, or upon the four sides, as shown in Fig. 1.

My design C consists in the ornamentation of the borders B in the manner substantially as shown in the drawings, said ornamentation representing a ribbon upon the face of one or more of the borders B, the same being concealed in plan view at stated intervals along the said face.

I claim—

The design for Christmas cards and other similar articles having the borders B and the ornamentation C upon the face of said borders, representing ribbon, the same being concealed in plan view at stated intervals along said face, 45 substantially as herein shown and described.

CHARLES E. BULLARD.

Witnesses:

JOHN C. DEWEY,
FRED. W. SMITH.
